UNITED STATES PATENT OFFICE.

HARRY B. NELSON, OF SAGINAW, MICHIGAN, ASSIGNOR TO NELSON BROTHERS CO., OF SAGINAW, MICHIGAN, A CORPORATION OF MICHIGAN.

ROD CONNECTION FOR PUMP HANDLES AND THE LIKE.

Application filed March 27, 1923. Serial No. 628,013.

This invention relates to an improved construction of joint for connecting a reciprocating rod and a movable head, as for example, the plunger rod of a kitchen pump and the head of the pump handle.

The objects of my improvement are to provide a simple and inexpensive construction that will enable such joints to be produced as articles of manufacture in large 10 quantities at relatively small expense. More specifically, this object is to so improve the construction of joints of the class referred to as to avoid the necessity for drilling, threading and tapping and the use of separate pintle bolts.

A further object is to provide a joint which will enable the end of the rod to be quickly attached to the handle and detached without removing bolts or nuts.

20 A still further object is to provide a construction enabling the joint to operate in use with a relatively small amount of friction and to this end my construction employs a steel surface of the rod bearing on a cast

25 iron surface of the pintle. The latter surface is, moreover, so shaped as to afford a maximum of bearing area on the rod.

With the foregoing and certain other objects in view which will appear later in the 30 specification, my invention comprises the devices described and claimed and the equivalents thereof.

In the drawings, Fig. 1 is a side view of a pump rod and handle embodying my 35 improvement.

Fig. 2 is an enlarged part sectional side view of my improved joint.

Fig. 3 is a front view of the head of the handle without the rod.

40 Fig. 4 is a part sectional detail showing the manner of assembling and disassembling the rod and handle.

Fig. 5 is a similar view showing the relative positions of the loop of the rod and head of the handle when the plunger is on its down stroke.

45 As is clearly shown in the drawings, 1 indicates a pump plunger or any other device to be actuated by means of the longitudinally reciprocating rod 2.

The rod 2 is connected to the handle 3 by my improved joint, the construction of which in its preferred form is shown in Figs. 2 to 5. I dispense with the usual transverse

pintle bolt through the head of the pump 55 handle and instead cast the handle with its head and the pintle 5 all in one piece.

The head 4 is bifurcated according to the usual practice in the manufacture of cast pump handles, but in my improved construction the pintle is cast integral with the sides or cheeks of the head. The pintle is preferably substantially spool-shaped, that is, of smaller diameter at its middle than at its 60 ends as shown in Fig. 3, so as to more closely conform to the shape of the hook 6 of rod 2. This hook is preferably made from a round bar and may be easily formed cold in 65 an ordinary punch press, since the hook is not closed, but U-shaped.

70 The hook is readily assembled upon the integral pintle 5 as shown in Fig. 4, by inverting the hook, as shown in dotted lines, inserting it into the bifurcated head, drawing it upward until the pintle 5 is embraced 75 by the hook and then turning the rod 2 down into its working position, as shown in Fig. 1.

On the up-stroke, or working stroke, the 80 hook 6 rests with large bearing area upon the spool-shaped pintle 5, the bearing pressure occurring between the top surface of the pintle 5 and the interior surface of hook 6, as shown in Fig. 2. On its down-stroke 85 the hook bears with its upper surface upon the under side of the pocket-like curved shoulder 7, as shown in Fig. 5. On the down-stroke the load is entirely removed from the pintle.

90 By the means above described I have produced a simple and inexpensive joint especially adapted to use on kitchen pumps and the like, but may be used in many other applications where a plunger rod is to be removably secured to a reciprocating head. It 95 will be noted that the joint, as an article of manufacture is fabricated without any machine work on the handle or pintle, and only one punch press operation is required to form the hook 6 on rod 2. The joint is thus 100 admirably adapted for economical quantity production.

105 Having thus described my invention, what I claim and desire to secure by Letters Patent is:

In a joint for the handles and plunger rods of pumps, a bifurcated head on said pump handle, said head having side walls

spaced apart, a pintle cast integral with the walls of said head and spanning the space therebetween, an interiorly curved shoulder member connecting the upper parts of said walls and spanning part of said space to a point directly above said pintle, a pump rod and a U-shaped hook on said rod partly

surrounding said pintle, and abutting against and actuated by the curved under side of said shoulder member when the handle is in use.

In testimony whereof, I affix my signature.

HARRY B. NELSON.
